UNITED STATES PATENT OFFICE.

HERBERT D. SMART, OF NASHUA, NEW HAMPSHIRE.

CAR SEAL.

Application filed February 27, 1923. Serial No. 621,540.

To all whom it may concern:

Be it known that I, HERBERT D. SMART, a citizen of the United States, residing at Nashua, in the county of Hillsborough and 5 State of New Hampshire, have invented certain new and useful Improvements in Car Seals, of which the following is a specification.

My invention relates to improvements in 10 car seals.

An important object of the invention is to provide a seal of the above mentioned character, which is formed in the minimum number of parts, and is extremely inexpensive to manufacture.

A further object of my invention is to provide a seal of the above mentioned character, which is practically impossible to open, without detection, and which is so 20 constructed that the strap element is powerfully locked within the keeper, when it is attempted to withdraw the same therefrom.

A further object of the invention is to provide a seal of the above mentioned character, which is extremely easy and quick to operate.

Other objects and advantages of the invention will be apparent during the course of the following description.

30 In the accompanying drawings, forming a part of this specification, and in which like numerals are employed to designate like parts throughout the same,

Figure 1 is a plan view of a strip of metal, 35 for forming the strap element,

Figure 2 is a central longitudinal sectional view through the same,

Figure 3 is a plan view of the keeper element,

40 Figure 4 is a longitudinal section taken on line 4—4 of Figure 3,

Figure 5 is a transverse section taken on line 5—5 of Figure 3,

45 Figure 6 is a longitudinal section through the seal, prior to the insertion of the tongue or free end of the strap element within the keeper, and,

Figure 7 is a similar view, showing the tongue in the inner locked position.

50 In the drawings, wherein for the purpose of illustration is shown a preferred embodiment of my invention, the numeral 10 designates a strap element, which is preferably formed of a strip of metal. This strap 55 element is bent transversely upon itself at 11, for producing an upper over-hanging

portion 12, extending substantially parallel with a lower or bottom portion 13, as shown. The upper over-hanging portion 12 is provided with a pair of outwardly bulging 60 chambers or pockets 14, stamped therefrom, forming inclined shoulders 15.

The lower or bottom portion 15 is provided with an outwardly inclined tongue 16, stamped therefrom, which affords an opening 17, as shown. This tongue is adapted to interlock with a downwardly inclined tongue 18, stamped from the upper portion 10 of the strap element 10, and providing an opening 19. The tongue 16 projects 70 through the opening 19 and the tongue 18 through the opening 17, when the parts are in the interlocked engagement.

The device further embodies a keeper or casing 20, which may be formed of a single 75 strip of sheet metal bent upon itself, into upper and lower portions 21 and 22. The edges of the upper portion 21 are bent outwardly horizontally, forming horizontal flanges 23, Figure 5, about which are bent 80 or crimped receiving flanges 24, formed upon the bottom portion 22. While it is preferred to construct the casing or keeper in this manner, the invention is not necessarily restricted to this procedure. The flanges 85 23 and 24 may be soldered or otherwise secured together, if desired, or the casing may be formed in an integral construction. The upper portion 21 is provided with outwardly projecting pockets 25, stamped therein, for receiving the pockets 14, providing 90 inclined walls 27, which engage with the inclined walls 15. The forward end of the strap element is inserted into the keeper or casing prior to the insertion of the opposite 95 end of the strap therein, or even before the flanges 24 are finally crimped or clamped into locking engagement with the flanges 23. The tongue 16 projects upwardly into one of the pockets 14, while the tongue 18 100 will project downwardly into a pocket 28, stamped or formed in the bottom portion 22 of the keeper.

As clearly illustrated in Figure 7, the free end of the strap element has been inserted within the keeper 20 and its tongue 18 engages behind the tongue 16. The free end of the strap element is therefore securely locked against longitudinal movement in an outwardly direction with respect to the 110 lower portion of the strap element. Should it be attempted to pull the entire strap ele-

ment from within the keeper or casing, the engaging inclined faces 15 and 27 positively prevent it, and in addition, serve to clamp the ends of the strap element together, also preventing relative movement of the free end of the strap element, thereby taking some of the pull off of the interlocking tongues, which might be straightened out, in the absence of this clamping action.

10 It is to be understood that the form of my invention herewith shown and described is to be taken as a preferred example of the same, and that various changes in the shape, size, and arrangement of parts may be resorted to without departing from the spirit of my invention, or the scope of the subjoined claims.

Having thus described my invention, I claim:

20 1. A car seal of the character described, comprising a strap element, said strap element being bent upon itself near one end forming a lower portion and an upper overhanging portion, said lower portion carrying a locking tongue, said upper portion being provided with outwardly bulging pockets forming inclined shoulders, said strap element being provided near its free end with an inclined locking tongue having co-
25 action with the first named locking tongue, and a casing receiving the bent end of the strap element and having outwardly bulging pockets to receive the pockets upon the upper overhanging portion, the pockets
30 upon the casing having both ends closed by inclined shoulders, whereby the overlapping portions of the strap element are clamped together upon the attempted withdrawal movement of the strap element from the
35 casing.

40 2. A car seal of the character described, comprising a strap element bent upon itself near one end forming a lower portion and an upper over-hanging portion, said lower portion carrying a locking tongue, said upper portion being provided with an outwardly

bulging pocket forming an inclined shoulder, said strap element being provided near its free end with a locking tongue for coaction with the first named locking tongue, and a casing receiving the bent end of the strap element and having an outwardly bulging pocket providing an inclined shoulder which closes the outer end of the last named pocket and coacts with the first named inclined shoulder, whereby the overlapping portions of the strap element are clamped together upon the attempted withdrawal movement of the strap element from the casing.

3. A car seal of the character described, comprising a strap element bent upon itself near one end forming oppositely arranged over-lapping portions, one portion having a locking tongue and the other portion being provided with an inclined shoulder, said strap element being provided near its free end with a coacting locking tongue, and a casing for receiving the bent end of the strap and having an inclined shoulder for coaction with the first named shoulder, said inclined shoulders serving to clamp the overlapping portions of the strap element together, upon the attempted withdrawal movement of the strap element from the casing.

4. A car seal of the character described, comprising a strap element bent upon itself, near one end providing over-lapping portions, one portion having a locking tongue and the other portion having an inclined shoulder, said strap being provided near its free end with a coacting locking tongue, and a casing receiving the bent end of the strap and having an inclined shoulder to coact with the first named inclined shoulder, said casing embodying a strip bent transversely upon itself forming oppositely arranged portions which are secured together at their edges.

In testimony whereof I affix my signature.

HERBERT D. SMART.
